UNITED STATES PATENT OFFICE.

EARL H. TATE, OF LOS ANGELES, CALIFORNIA.

INCANDESCENT ELECTRIC LAMP.

1,036,744.

Specification of Letters Patent. Patented Aug. 27, 1912.

Application filed September 5, 1911. Serial No. 847,637.

To all whom it may concern:

Be it known that I, EARL H. TATE, a citizen of the United States, residing at Los Angeles, in the county of Los Angeles and State of California, have invented certain new and useful Improvements in Incandescent Electric Lamps; and I do declare the following to be a full, clear, and exact description of the invention, such as will enable others skilled in the art to which it appertains to make and use the same.

This invention relates to improvements in incandescent electric lamps.

One object of the invention is to provide a lamp of this character having arranged therein means whereby the lamp is cooled and the bulb thus prevented from being broken by the intense heat generated from high candle power lights.

Another object is to provide a lamp of this character having an improved construction and arrangement of filaments and means for supporting the same.

With these and other objects in view, the invention consists of certain novel features of construction, and the combination and arrangement of parts as will be more fully described and claimed.

In the accompanying drawings: Figure 1 is a side view of my improved lamp, parts being broken away and in section; Fig. 2 is a vertical sectional view thereof; Fig. 3 is a top plan view; Fig. 4 is a bottom plan view of the glass cap for closing the inner end of the bulb and for forming a support for the filament holding and heat discharging element of the lamp; Fig. 5 is a horizontal sectional view on the line 5—5 of Fig. 2; Fig. 6 is a similar view on the line 6—6 of Fig. 2.

Referring more particularly to the drawing, 1 denotes the glass bulb of the lamp, said bulb being of the usual or any desired shape. To the inner end of the bulb is fused or otherwise firmly secured a circular convex cap 2 formed of glass or other suitable insulating or non-conducting material. In the center of the lower side of the cap is formed a depending or inwardly extending frusto-conical shaped projection 4 around which in the inner side of the cap is formed an annular recess 5. Through the projection 4 and central portion of the cap is formed a series of air circulating passages or perforations 6 the purpose of which will be hereinafter more fully described.

Arranged on the cap 2 and inner end of

the bulb is a hollow metal base or shell 7 which is preferably threaded as shown and otherwise corresponds to the usual base of an incandescent lamp. The base or shell 7 has arranged in its outer end a disk 8 of insulating material to the outer side of which is secured a terminal or contact plate 9. On the inner edge of the base or shell 7 is formed a skirt 10 which extends over the outer edge of the cap and the adjacent portion of the bulb as shown. The skirt is cemented or otherwise rigidly secured to the outer edge of the cap. Through the cement and between the surface of the cap and adjacent portion of the skirt are formed two or more air passages 8 the upper and inner ends of which communicate with the space in the hollow shell or base 7 and the outer ends of which communicate with slots 11 formed in the skirt or extension 10 of the base or shell. The passages 6 in the cap 2 also communicate with the space in the shell or base 7 as shown.

Within the bulb 1 is a combined filament supporting and heat discharging mechanism comprising a pendant narrow cone 12 formed of tin, glass or other suitable insulating or non-conducting material, said cone projecting into the bulb to the proper distance and having formed on its larger open end an annular radially projecting attaching flange 18 which fits and is adapted to be secured within the annular recess 5 in the inner side of the cap 2 by fusing or in any other suitable manner. When the cone is thus secured to the cap the projection 4 on the inner side of the cap extends into and closely fits the open end of the cone as shown. Preferably, though not necessarily arranged in the cone 12 is a cone shaped metallic lining 14 which extends to within a short distance of the open end of the cone 12 as shown. The lining 14 has a bright reflecting surface and may be constructed of tin foil or thin sheet metal or may be simply in the form of a metallic coating applied to the inner side of the cone.

Arranged through and fused or welded in the sides of the cone 12 and projecting through the lining 14 adjacent to the open end thereof are diagonally arranged current conducting pins 15 which serve to hold the lining 14 in place and to the opposite ends of which are connected the current conducting wires 16 and 17 of the lamp. The current conducting wires 16 and 17 pass out of

the lamp through the passages 6 in the cap 2 and the outer end of the wire 16 is connected to the terminal or contact plate 9 while the outer end of the wire 17 is connected to the shell or base 7 as shown.

5 Arranged on the upper portion of the cone 12 is an upper filament supporting disk 18 formed of glass or other non-conducting material, said disk having formed therein a centrally disposed passage to receive the cone. Around the passage in the disk 18 is formed an annular laterally projecting flange 19 which closely fits the side of the cone 12 and forms an increased bearing surface for the disk. In the outer portion of the disk are molded angularly bent substantially V-shaped filament supporting wires 20 the ends of which project beyond the outer edge of the disk and form hangers to which the ends of the filaments are soldered or otherwise firmly secured. One of the ends of the wires 20 is longer and projects a greater distance from the edge of the disk than its companion end so that when the filaments are secured to said ends one strand of the filaments will be disposed nearer to the cone than the other strand. Secured to the cone near its smaller end and spaced a suitable distance from the disk 18 is a second filament holding disk 21 which is constructed in a similar manner but is somewhat smaller than the disk 18. Embedded in the disk 21 is a series of radially projecting filament engaging wires 22 in the outer ends of which are formed bends or hooks which engage the loops of the filaments and hold the latter in proper position relative to the outer surfaces of the cone. The inner ends of the conducting wires 16 and 17 are connected to the ends of the wires 20 or adjacent ends of the filaments as shown. By providing a cone shaped filament support constructed and arranged as herein shown and described together with the perforated hollow base or shell 7 and the perforated cap 2 the heat from the incandescent filaments will be absorbed by the glass cone and its metal lining and the heat thus absorbed will form a vortex in the cones and will thus be rapidly drawn out through the perforations 6 in the cap 2 and discharged through the passages 8 and slots 11 in the skirt of the shell or base 7. By arranging one strand of each of the filaments closer to the surface of the cone than the other, the heat from these strands or filaments will be absorbed by the cone before it can reach the bulb, thus relieving the latter of this much of the heat generated by the filaments.

60 From the foregoing description taken in connection with the accompanying drawings the construction and operation of the invention will be readily understood without requiring a more extended explanation.

65 Various changes in the form, proportion

and the minor details of construction may be resorted to without departing from the principle or sacrificing any of the advantages of the invention as claimed.

Having thus described my invention, what

70 I claim is:

1. In an incandescent electric lamp, a bulb, a non-conducting cap cemented to the inner end of said bulb and having a frusto-conical projection at its center extending 75 into the bulb, a pair of perforations through the cap and projection, and a groove around the latter on the inner face of the cap, a hollow metal base with whose interior said perforations communicate, the base having 80 a skirt secured to the cap and bulb and pierced with discharge slots also communicating with the interior of the base, a hollow element having a flange secured in said recess so that its interior communicates with said perforations, a lining within this element, filament-carrying devices mounted on the element, pins through its wall, and wires leading from said devices through said pins and perforations and to contact points 90 carried by said base.

2. In an incandescent electric lamp, a bulb, a non-conducting cap secured to the inner end of said bulb, said cap having formed therein a series of perforations and 95 an annular recess, a narrow pendant cone formed of insulating material arranged in said bulb, a flange formed on the open end of said cone and secured in the recess in said cap whereby the cone is held in operative position in the bulb, a frusto-conical projection formed on the inner side of said cap and extending into said cone, and a hollow metal base having a skirt surrounding said cap and the adjacent end of the bulb, said skirt 100 being cemented to the edge of the cap and having formed therein heat discharging slots, said cement connection between the skirt and the cap having formed therein passages communicating with said slots in 110 the skirt and the space in said hollow base.

3. In an incandescent electric lamp, a bulb, a hollow cone in said bulb, upper and lower non-conducting disks on said cone, filament supporting wires arranged in said 115 upper disk, said wires having angularly projecting ends, one of which is of greater length than the other whereby some of the filament strands are closer to said cone than the others, filament engaging wires arranged 120 in said lower filament supporting disk, said wires having their outer ends bent to form notches adapted to engage the loops of the filaments, and means whereby the heat within said cone is discharged from the lamp.

4. In an incandescent electric lamp, a bulb, a hollow cone in said bulb, upper and lower non-conducting filament supporting disks on said cone, filament supporting wires carried by said disks, a perforated cap on 130

the inner end of the bulb and supporting said cone, and a hollow base secured to said cap and having heat discharging openings whereby the heat from the cone is discharged 5 to the exterior.

5. In an incandescent electric lamp, a bulb, a hollow cone shaped filament supporting and heat absorbing cone arranged in said bulb, upper and lower non-conducting filament supporting disks arranged on said cone, filament supporting wires arranged in said upper disk, said wires having angularly projecting ends, one of which is of greater length than the other whereby some 10 of the filament strands are closer to said cone than the others, filament engaging wires arranged in said lower filament support-

ing disk, said wires having their outer ends bent to form notches adapted to engage the looped ends of the filament, a perforated 20 cap arranged on the inner end of the bulb and adapted to support said cone, a hollow base or shell secured to said cap and to the adjacent end of the bulb, said base or shell having formed therein heat discharging 25 openings whereby the heat from the cone is discharged from the lamp.

In testimony whereof I have hereunto set my hand in presence of two subscribing witnesses.

EARL H. TATE.
